UNITED STATES PATENT OFFICE

160,920

CONDIMENT SHAKER

George Brooks, Jr., St. Paul, Minn.

Application January 28, 1950, Serial No. 7,541

Term of patent 3½ years

(Cl. D44—22)

To all whom it may concern:

Be it known that I, George Brooks, Jr., a citizen of the United States, residing in the city of St. Paul, county of Ramsey, and State of Minnesota, have invented a new, original, and ornamental Design for a Condiment Shaker, of which the following is a specification, reference being had to the accompanying drawing, forming a part hereof.

In the drawing:

Fig. 2 is a front elevational view of the same;
Fig. 3 is a side elevational view of the same;
Fig. 4 is a top plan view thereof, and
Fig. 5 is a bottom plan view thereof.

I claim:

The ornamental design for a condiment shaker, as shown.

GEORGE BROOKS, JR.
